UNITED STATES PATENT OFFICE.

MILES EDWARD LOEHR, OF CLAYPOOL, INDIANA.

ACETYLENE-GENERATOR.

1,156,788.

Specification of Letters Patent. Patented Oct. 12, 1915.

Application filed June 26, 1913. Serial No. 775,991.

To all whom it may concern:

Be it known that I, MILES EDWARD LOEHR, a citizen of the United States, residing at Claypool, in the county of Kosciusko and State of Indiana, have invented certain new and useful Improvements in Acetylene-Generators; and I do hereby declare the following to be a full, clear, and exact description of the invention, such as will enable others skilled in the art to which it appertains to make and use the same.

This invention relates to new and useful improvements in acetylene gas generators of the type embodying essentially a generator, a gasometer, and carbid-feed mechanism automatically operable by variation of volume of gas in the gasometer for regulating the quantity of gas generated.

An object of the invention is to construct the carbid-feed mechanism in such manner that while the volume of the generated gas is increasing the feed of the carbid into the generating chamber will be automatically cut off, but when, by reason of the exit of the gas from the gasometer through the service pipe, the volume decreases, the feeding operation will be automatically resumed.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 represents a vertical central sectional view, partly broken away, through the generator, Fig. 2 represents an enlarged sectional view, partly broken away, illustrating the carbid feed mechanism in detail, Fig. 3 represents a detail view of the feed wheel employed in controlling the dispensing of carbid from the carbid container into the generating chamber. Fig. 4 represents an enlarged plan view of the ratchet connection between the feed shaft and stub shaft. Fig. 5 represents a detail sectional view on the line 5—5 of Fig. 1, and, Fig. 6 represents a detail sectional view on the line 6—6 of Fig. 2. Referring to the drawings in detail, wherein similar reference numerals desig-

nate corresponding parts throughout the several views, the numeral 11 indicates a cylindrical metallic shell or casing which, if desired, may be mounted within an outer casing (not shown) and the upper terminal of which is open and is equipped with the lid or cover 12 of the usual sealing flange type, and is provided with a centrally disposed sight opening, as at 13. The member 11 is formed at its lower terminal with a funnel-shaped mouth, as at 14.

The generating chamber, designated by the letter A, is arranged at the lower end of the inner casing 11 and is formed by a secondary inner shell 33 having a flared mouth or flange 34, which is cylindrical in shape and is of less diameter than the member 11, being secured in spaced relation thereto by bolting, soldering, or otherwise securing the flared mouth or flange 34 to the casing 11. It will be apparent that an annular chamber, to be hereinafter designated by the letter B, is formed between the members 11 and 33. In this chamber is arranged the gasometer which will be next described.

The gasometer consists essentially in a gas bell 35, which is annular in shape and is formed by a pair of spaced annular walls 36 and 37, the upper edges of which are connected and sealed by a ring plate 38, while the lower portion of the bell is unsealed to permit water which is in practice poured into the chamber B to enter the space between the walls 36 and 37.

The gas generated in the chamber A passes into the gas bell through a pipe 39, the upper end of which carries a funnel-shaped filter, designated as an entirety in Fig. 1 by the numeral 40. The pipe is secured in position in the member 40 by a layer of suitable porous filtering material 41. As illustrated in detail in Fig. 5, this filter 40 is a substantially inverted funnel-shaped shell, so that as the gas issues from the upper end of the pipe 39 it must, before entering the space between the water level in the chamber B and the ring 38 pass through the orifices 42 of the shell, and then through the water. It will be observed that the gas is thus thoroughly filtered and cooled before being let into the service pipe.

A service pipe 22 is connected with a branch pipe 23 which latter is extended through the wall of the casing 11 and upwardly within the gas bell 35, having its upper open end disposed above the level of the

water in said bell. The generating chamber A is adapted to be partially filled with water by a water pipe 17 extended through the lower portion of the wall of the casing 11.

70 The gas bell is operatively connected to the carbid-feed mechanism, so that the feeding of the carbid is automatically regulated by the variation of the volume of the gas in the generating chamber. This carbid-feed mechanism is all arranged interiorly of a cylindrical casing 43, which is slightly greater in diameter than the casing 33 and is telescopically and rigidly secured thereon.

75 80 The casing 43 carries adjacent its lower end an internally arranged substantially funnel-shaped shell 44, which may be welded, bolted, or otherwise secured in assembled position, and which is designed to support the 85 casing in assembled position on the member 33. As illustrated in detail in Fig. 3, the apex portion of the shell 44 is provided with a closure plate 45, centrally of which is journaled the lower terminal of a feed shaft 90 46. On the shaft 46 is carried a feed wheel 47, which is arranged to rotate with the shaft and to urge the carbid which is contained within the casing 43 to an opening 48 formed at one side of the plate 45. Below the opening 48 is secured a tubular chute 49, the lower end of which is normally closed by a pivoted gate valve 50, which carries a balance arm 51 and a balance weight 52 adjustably mounted thereon 100 with a set screw 53. The gate valve 50 is normally held in closed position by the balance weight 52, but when the shaft 46 has been rotated sufficiently to deposit the desired amount of carbid in the chute 49 the 105 effect of the member 52 is overcome, and the carbid drops into the generating chamber.

110 The member 52 may, of course, be adjustable on the arm 51 to effect the deposit of the carbid into the generating chamber in any desired predetermined quantities. In the preferred embodiment of this invention a pound of carbid is deposited in the generating chamber by the valve 50 as a charge.

115 The shaft 46 extends vertically and centrally within the casing 43 and is journaled for the greater part of its length in a tube or sleeve 54, the upper terminal of which is secured, as at 55, centrally of a cover or top 56, and the lower terminal of which is secured, as at 57, to an inclined partition plate 58, which forms a bottom wall for the carbid chamber C. An opening is formed in the member 58 and at one edge thereof, as at 59, to permit the carbid to pass from the 120 chamber C down the inclined wall of the partition plate 58 through the opening 59 and to the feed wheel 47. The top 56 is, of course, provided with an inlet, as at 60 to permit the operator to fill the carbid chamber 125 C in the usual manner.

The shaft 46 is designed to be rotated only during the dropping of the gas bell, so that while the volume is increasing in the generating chamber, the bell will move upward without causing the deposit of any more carbid in the generating chamber. As a means, therefore, for operatively connecting the gas bell to the shaft 46 in such manner that the shaft will be rotated only upon the downward movement of the bell, there has been provided a stub shaft 61, journaled at its upper terminal in a horizontal member 62 of a frame 63, mounted on the top 56. A pair of fusees 64 and 65 are keyed on the stub shaft 61 and are adapted to co- 15 operate in winding the gas bell chains 66 and 67, when the gas bell moves upwardly under pressure. These two fusees 64 and 65 may be formed integrally and are arranged oppositely as regards their relation to the stub 20 shaft 61. The upper terminal of the shaft 46 extends through a bearing 68 upwardly into the lower fusee 65, in which it is freely journaled. A ratchet wheel 69 is secured to or formed integrally with an adjustable collar 70, which is held in the desired position on the shaft 46 by a set screw 71. This ratchet wheel 69 is arranged for engagement by a pivoted pawl 72 which is pivotally secured to the lower face of the lower 30 fusee 65. When the gas bell moves upwardly, the stub shaft 61 is rotated by the gravity pull of a weight 73, which is operatively connected to the shaft 61 by a cable 74, which plays over a pulley 75 secured to 35 the frame 63 and is designed to wind and unwind on a pulley 76, keyed on the stub shaft 61 adjacent its upper terminal. The pawl 72 is designed to move around the ratchet wheel 69 without positively engaging it during the rotation of the stub shaft 61 by the weight 73, during the upward movement of the gas bell, but when the gas bell again moves downwardly the pawl 72 positively engages the teeth of the ratchet 40 wheel 69 and effects an operative connection between the stub shaft 61 and the feed wheel shaft 46.

When the gas bell 35 moves upwardly the chains 66 and 67 which are connected to 50 the gas bell and to the fusees 64 and 65 are wound upon the fusees 64 and 65 hence the weight 73 connected with the stub shaft 61 is permitted a downward movement upon the slackening of the chains 66 and 67 thus 55 causing the fusee 64 and 65 carried upon the shaft 61 to rotate and subsequently wind the chains thereon. When the gas bell 35 moves downwardly owing to the decrease of the volume of gas the fusees 64 and 65 are 60 rotated and the pawl 72 carried by the fusee 65 engages the ratchet wheel 69 causing the shaft 46 to turn and permit a charge of carbid to be deposited within the generating chamber A. 65

In reduction to practice, I have found that the form of my invention, illustrated in the drawings and referred to in the above description, as the preferred embodiment, is 5 the most practical and efficient; yet, realizing that the conditions concurrent with the adoption of my device will necessarily vary, I desire to emphasize the fact that various minor changes in details of construction, proportion and arrangement of parts may be resorted to, when required, 10 without sacrificing any of the advantages of my invention, as defined in the appended claims.

15 What is claimed is:

1. In an acetylene generator, a generating chamber, a carbid hopper arranged to feed carbid into said generating chamber, a shaft 20 rotatably mounted within the carbid hopper, means carried by the shaft for feeding a charge of carbid to the generating chamber during the rotation of the shaft, a stub shaft rotatable relative to the first mentioned shaft, a pair of fusees secured to the 25 stub shaft, a gas bell, flexible connections between said drums and said gas bell, means tending to rotate said stub shaft in one direction to wind said flexible connections on said fusees during the upward movement of said gas bell, and means for locking the first and second mentioned shafts together for rotation in the opposite 30 direction during the downward movement of said gas bell.

35 2. In an acetylene generator, a main outer casing, an inner casing mounted within said outer casing, a generating chamber formed in said inner casing, a removable carbid 40 hopper arranged in said inner casing, means for feeding a charge of carbid to the generating chamber, comprising a rotatable shaft, a plurality of radial arms on the lower terminal of said shaft, and arranged

to force the carbid through an opening in 45 the hopper into said generating chamber, a pair of fusees, means for rotatably supporting said fusees, a gas bell, a plurality of flexible elements connecting the gas bell with the fusees and adapted to be wound 50 thereon upon the upward movement of the gas bell, means carried by one of the fusees for rotating said first named shaft upon the movement of the fusees in one direction, means for rotating the fusees upon the upward movement of the gas bell, said gas bell adapted to rotate said fusees when moving downwardly to operate said first named shaft and permit a charge of carbid 55 to be deposited into the generating chamber. 60

3. In an acetylene generator, a generating chamber, a carbid hopper arranged to feed carbid into said generating chamber, a shaft 65 rotatably mounted within said carbid hopper, means carried by the shaft for feeding a charge of carbid to the generating chamber during the rotation of the shaft, a stub shaft rotatable relative to the first mentioned shaft, a pair of fusees secured to the 70 stub shaft, a gas bell, flexible connections between said fusees and said bell, means tending to rotate said stub shaft in one direction to wind said flexible connections on said fusees during the upward movement of 75 said gas bell including a gravity actuated weight and a flexible member trained over a pulley on said stub shaft, and means for locking the first and second mentioned shafts together for rotation in the opposite 80 direction during the downward movement of said gas bell.

In testimony whereof I affix my signature in presence of two witnesses.

MILES EDWARD LOEHR.
